UNITED STATES PATENT OFFICE.

ALEXANDRE M. GREAN, OF MOUNT VERNON, NEW YORK.

COLLAR-SUPPORTER.

1,231,595.

Specification of Letters Patent.

Patented July 3, 1917.

Application filed January 12, 1916. Serial No. 71,761.

To all whom it may concern:

Be it known that I, ALEXANDRE M. GREAN, a citizen of the United States, residing at Mount Vernon, in the county of Westchester and State of New York, have invented new and useful Improvements in Collar-Supporters, of which the following is a specification.

The present invention relates to collar supporters, and the primary object is to provide a simple structure of a novel character that can be inexpensively manufactured and will provide an extended bearing or support for the collar to which it is applied.

Several embodiments of the invention are illustrated in the accompanying drawings, wherein:

Figure 1 is a view in elevation of an embodiment of the invention.

Fig. 2 is a view of the blank from which the same can be manufactured.

Fig. 3 is a side elevation of still another form of construction.

Fig. 4 is a blank therefor.

Fig. 5 is another embodiment.

Fig. 6 is the blank before twisting.

Fig. 7 is a view in elevation of another form of construction, and

Fig. 8 is a view of the blank therefor.

Fig. 9 is a view of an embodiment similar to Fig. 7, but illustrating the central arm as heavier than the side arms.

Fig. 10 is a view in elevation of the blank from which Fig. 9 is made.

Similar reference numerals designate corresponding parts in all the figures of the drawings.

In each of the structures disclosed, the supporter is preferably made of a single length of metallic wire, but the material is relatively unimportant, and by the term "wire," it is intended to include any substance in the form of an elongated body, filament or strand suitable for the purpose.

Referring to the embodiment illustrated in Figs. 1 and 2, a shank arm 11^a is provided, comprising a plurality of twisted strands, and from one end of the same project divergently disposed arms 13^a and 14^a.

Each of these arms also consists of two strands twisted together. The free ends of the arms 13^a and 14^a are provided with loops forming securing eyes 16^a, and the free end of the shank arm 11^a is bodily bent into a loop to form a securing eye 15^a. As shown in Fig. 2, this type is produced from a single

length of wire doubled at its center, the doubled portion being formed into a general Y shape, the arms of the Y being twisted to form the arms 13^a and 14^a, and the longer portion forming the shank 11^a.

A somewhat similar structure in appearance, but one differing slightly in structure, is illustrated in Figs. 3 and 4. The general appearance of this supporter is like the letter Y, but, as will be evident by reference to the blank shown in Fig. 4, the shank arm, which is designated 11^b, consists of four strands, whereas the radiating arms 13^b and 14^b, each comprises two strands, each of said radiating arms being an extension of two of the strands of the shank arm. The two strands of each of the arms 13^b and 14^b are twisted together, leaving terminal securing eyes 16^b, while the four strands of the shank 11^b are also twisted together. It will be noted that two of the strands of the arm 11^b are integrally joined by a terminal loop which is left to produce the terminal securing eye 15^b, the outstanding ends 17^b of the blank being clipped off in completing the collar supporter.

Another embodiment of the structure is illustrated in Figs. 5 and 6. In this form, each arm consists of two strands, the shank arm 11^c having the ends of its strands extending to form strands in each of the divergent arms 13^c and 14^c, which extensions are doubled back to produce the two strands in each of said latter arms. These strands are twisted together, so that terminal securing eyes 16^c are produced, and the terminal loop of the blank forming the shank arm 11^c produces a terminal eye 15^c. In this instance, the ends 17^c of the blank are located at the point from which the various arms radiate, but are clipped off so that they will not be in a position to prick the wearer.

Another embodiment involving the same general invention is illustrated in Figs. 7 and 8. In this case, the three arms 11^d, 13^d and 14^d, each consists of two strands twisted together and have at their free ends terminal securing eyes 15^d and 16^d. They radiate from a common point in a divergent direction, but are all located within a compass of one hundred and eighty degrees. This supporter, as will be clear by reference to Fig. 8 is formed from a single length of wire bent to form the arms or fingers which are afterward twisted together, the ends 17^d being clipped off to complete the structure.

In the embodiment illustrated in Figs. 9 and 10 the supporter is of the same shape as that shown in Fig. 7, but in this embodiment, the central arm 11^e is heavier than the 5 side arms 13^e and 14^e, being formed of four strands, as will be evident by reference to Fig. 10. Each of the free ends of the arms are provided with terminal securing eyes 15^e and 16^e, and the ends 17^e of the blank or 10 wire are located at the free end of the central arm 11^e, but are clipped off so that the eye 15^e will project beyond the same.

From the foregoing, it is thought that the 15 construction, operation, and many advantages of the herein described invention will be apparent to those skilled in the art, without further description, and it will be understood that various changes in the size, shape, proportion, and minor details of construction, may be resorted to without departing from the spirit or sacrificing any of the advantages of the invention.

Having thus fully described my invention, what I claim as new, and desire to secure by Letters Patent, is:—

1. A collar supporter formed from a single length of wire and comprising at least three arms radiating from a common center, each arm consisting of a plurality of strands twisted together and forming a 30 terminal securing loop or eye at the free end of the arm, the ends of said length of wire being located substantially at the said common center.

2. A filamentary collar supporter formed from a single length of wire comprising a stem and a plurality of branches extending from one end thereof, said stem and branches each being formed of a plurality 40 of strands of said length of wire twisted together and an eye formed at the free end of the stem and at the extremity of each branch.

3. A filamentary collar supporter formed

from a single length of wire comprising a 45 stem and a plurality of branches extending from one end thereof, said stem and branches each being formed of an equal number of a plurality of strands of said length of wire twisted together, and an eye 50 formed at the free end of the stem and at the extremity of each branch.

4. A filamentary collar supporter comprising a stem and a plurality of branches extending from one end thereof, the stem 55 and branches each being formed of a plurality of strands of wire twisted together and an eye located at the free end of the stem and at the extremity of each branch.

5. A filamentary collar supporter comprising a stem and a plurality of branches extending from one end thereof, the stem and branches each being formed of a plurality of strands of wire twisted together 65 and an eye located at the free end of the stem and at the extremity of each branch each of said eyes comprising a continuous loop formed by doubling the wire to produce the plurality of strands.

6. A filamentary collar supporter comprising at least three arms radiating from a common center, each arm comprising a plurality of strands twisted together substantially throughout the length of the arm and each having an eye at its free end 75 formed of a continuous closed loop produced by doubling the wire, the ends of the wire terminating at the point of juncture of the arms and so disposed that they will not prick the wearer.

In testimony whereof I have hereunto set my hand in presence of two subscribing witnesses.

ALEXANDRE M. GREAN.
